UNITED STATES PATENT OFFICE

GEORGE A. VAUGHN, OF NEWTON, IOWA, ASSIGNOR TO THE PARSONS COMPANY, OF NEWTON, IOWA

OUTRIGGER FOR CRANES OR THE LIKE

Application filed July 5, 1927. Serial No. 202,311.

My invention has to do with an outrigger construction forming part of a crane or similar machine for handling heavy loads.

More particularly, it is my object to provide an outrigger structure having parts so constructed and arranged as to be conveniently anchored to the rails of a track on which the crane travels for anchoring the crane against tilting, overturning or racking.

Another purpose is to provide such an equipment by which the supporting derrick or A frame or the like over which the hoisting line is drawn may be directly supported on the rail without imposing the load carried by the A frame first on the main frame of the crane and then on the rail.

It is my object also to provide in such a device a number of novel features in the construction of mounting of the outrigger clamps.

With these and other objects in view, my invention consists in the construction, arrangement and combination of the various parts of my outrigger whereby the objects contemplated are attained, as hereinafter more fully set forth, pointed out in my claims, and illustrated in the accompanying drawings, in which:

Figure 1 is a side elevation of a crane of the boom hoist type equipped with an outrigger construction embodying my invention.

Figure 2 shows a vertical, transverse, sectional view taken on the line 2—2 of Figure 1.

Figure 3 is a perspective view of the parts of the outrigger clamp disassembled.

Figure 4 is an enlarged view in side elevation of one of the outrigger clamps and parts of the crane taken from the opposite side of that shown in Figure 1; and

Figure 5 is a detail, sectional view taken on the line 5—5 of Figure 4.

I have found in the designing of cranes for use on railroad tracks that a relatively light weight crane can be used for doing comparatively heavy work if proper means are provided for anchoring the crane on the rails against tilting and for supporting all or part of the load on the rails by the anchoring means employed.

In the drawings herewith, I have used the reference character 10 to indicate generally the rails of a track resting on the ties 12.

I have indicated the frame B of a crane, which frame is supported on wheels 14 on the rails 10.

I may say that in the drawings herewith, I have shown the crane structure generally in somewhat diagrammatic form, because it is my intention to show only enough of the crane to illustrate my present invention.

At one end of the crane, there is supported an A frame A, having the upwardly and forwardly inclined side members 16 supported on the main frame B and connected together by a cross member 18 at their upper ends.

A boom 20 is pivoted on the frame B adjacent to the lower end of the A frame A. The boom 20 is supported in any suitable way for vertical, pivotal movement and also for horizontal, swinging movement.

The structure for this mounting is old and in itself forms no part of my present invention.

A cable rigging 22 is provided for connecting the outer end of the boom with the upper end of the A frame for supporting the outer end of the boom at different heights.

By this structure, it is obvious, of course, that a part of the load imposed on the boom is imposed on the A frame, which is rigidly braced by the braces 24.

I have in mind particularly that condition of the crane when the boom is swung to extend laterally as shown for instance in Figures 1 and 2.

For instance, as shown in Figure 2, a substantial part of the load will be imposed upon that member 16 of the A frame on the side adjacent to the boom 20, whereas the other member 16 will tend to be pulled upwardly.

For rigidly anchoring the crane and especially the A frame to carry part of this load on the A frame and also to hold the crane against tilting, I have provided the outrigger structure, which I shall now more fully describe.

The main frame B has the longitudinal, side members 26, which are ordinarily in the

form of channel bars opening inwardly toward each other.

The A frame members 16 are supported on the respective channel bars 26.

On each side of the machine, a bracket is employed comprising the plate 28 having at its upper end the inclined portion 29. The plate 28 is riveted or bolted to the frame member 26 and the extension 29 to the A frame member 16.

Projecting outwardly from the plate 28 and extension 29 is a sturdy reinforcing rib 30.

Formed on the lower end of the plate 28 are spaced aligned journals 32. (Figure 3.) Pivotedly supported on the plate 28 is a clamp member indicated generally at C and comprising the arm 34 having at its upper end the journal 36 received between the journals 32 and pivotally connected therewith by means of a pin 38 detachably received in the journals 32 and 36.

At the lower end of the arm 34 are downwardly projecting spaced arm members 40, having registering holes 42, preferably substantially rectangular in outline to receive the wedge 44.

Extending downwardly from the arm portions 40 are arm portions 40^a in the form of spaced side plates connected together as at 46 at their lower ends and at one side of the vertical axis of the arm 34, as clearly shown in Figure 3.

In the arm members 40^a are registering elongated holes 48.

The wedge 44 may be connected with one of the arm members 40^a by means of a chain 50 to prevent loss.

I provide a second clamp member indicated generally at D in Figure 3, comprising an upper arm member 52 having an elongated hole 54 therein, and having formed on its lower end the clamp face 56 extending in both directions from the arm 52.

The clamp D is provided with two spaced, reinforcing flanges 58 on opposite sides of the lower part 52^a of the arm 52. The clamp face 56 extends across the flanges 58 and the arm portion 52^a only at the lower part thereof.

The flanges 58 project above the clamp face 56 and are formed at their upper portions with journals 60 registering with each other and with the hole 62 in the upper part of the arm portion 52^a as illustrated in Figure 3.

In assembling the clamp members C and D, the upper part of the arm portions 52 is slipped between the arm members 40 with the arm members 40^a received between the journals 60 and the arm member 52^a.

A pin 64 shown in Figure 5 is extended through the journals 60 and the hole 62 and the elongated holes 48.

When this has been done, it will be seen that the clamp member D has some play on the clamp member C.

When the outrigger device is not in use, it may be swung to the dotted line position shown in Figure 5, or the pin 38 may be removed and the clamp members C and D assembled together by means of the pin 64 70 may be laid in the tool box.

When the parts are assembled and it is desired to use the outrigger device, the lower jaw portion of the clamp member D is swung away from the downwardly projecting clamp shoulder or face 46 connecting the arm members 40^a, so as to receive between the face 46 and the clamp face 56 the ball 66 of the rail 10. 75

On account of the play allowed by reason of the fact that the holes 48 are elongated, 80 it will be seen that that portion of the clamp member D, which engages the rail may be vertically adjusted and also laterally adjusted to some degree on account of the play of the pin 64 in the holes 48. 85

When the clamp members have been placed over the rail, the wedge 44 is slipped through the holes 42 and 54 for drawing the clamp members D and C tightly into engagement with the rail. 90

It will be noticed that the clamp face 56 has an inturned portion 56^a at its lower edge for engaging under the ball of the rail.

The outrigger on the other side of the crane is clamped to the rail in the same way. 95

When the outrigger is thus clamped to the rail, it will be noted that the crane will be anchored against tilting movement and also that there is a rigid steady connection between the A frame and the frame B and the 100 rail.

Thus, when, as illustrated in Figure 2, a heavy load 70 is carried by the boom 20, the down thrust on the A frame member 16 adjacent to the boom will be transmitted directly to the rail to a considerable extent, instead of being transmitted through the frame B. 105

Similarly, the up-pull on the other member 16 will be transmitted to the opposite rail directly instead of through the frame B. 110

It will thus be seen that I have provided an outrigger structure, which makes it possible to build a very steady A frame for carrying extremely heavy loads without putting the weight in the frame B that would otherwise be necessary, and it is therefore possible to build the entire crane with less material and at substantially less expense for handling heavy loads than would otherwise be possible. 115

Changes can be made in the details of the structure and arrangement of the parts of my improved outrigger structure, and it is my intention to cover by my claims any modified forms of structure or use of mechanical equivalents, which may be reasonably included within their scope. 120

I claim as my invention:

1. In a structure of the class described, the combination of a main frame mounted on wheels adapted to travel on rails, an upright 130

member supported on said main frame, and an outrigger comprising a bracket rigidly connected with said upright member, a clamp member pivoted to said bracket, a second clamp member having a loose pivotal connection with the first clamp member, and means for rigidly connecting the clamp members.

2. In an outrigger structure, a bracket, a clamp member pivoted to said bracket, a second clamp member having a loose pivotal connection with said first clamp member, and means for rigidly connecting said clamp members together.

3. In an outrigger structure, a bracket, a clamp member pivoted thereon, a second clamp member loosely pivoted to said first clamp member for vertical and horizontal adjustment with relation thereto, and means for rigidly fastening the clamp members together.

4. In an outrigger structure, a clamp member, means for pivotally supporting said clamp member, a second clamp member having a loose pivotal mounting on the first clamp member, and means for rigidly connecting said clamp members together.

5. In an outrigger structure, a clamp member, means for pivotally supporting said clamp member, a second clamp member, one of said clamp members having spaced elongated holes and the other having a journal member, a pin extended through said holes and journal member for loosely pivoting the clamp members together, said clamp members being provided with elongated holes, and a wedge adapted to be extended through said last-described holes for rigidly securing the clamp members together.

6. In a structure of the class described, a frame mounted on wheels adapted to travel on rails, an outrigger device on said frame comprising a clamp having relatively adjustable jaw members, and means for rigidly connecting the jaw members together for gripping a rail and affording a rigid connection between said frame and the rail.

Des Moines, Iowa, June 23, 1927.

GEORGE A. VAUGHN.
